FIG. 1.

FIG. 2.

INVENTOR

FIG. 4. Joseph Meditz,
BY
Maurice Block

ATTORNEY

UNITED STATES PATENT OFFICE.

JOSEPH MEDITZ, OF BROOKLYN, NEW YORK.

SPRING.

1,308,601.

Specification of Letters Patent.

Patented July 1, 1919.

Application filed March 17, 1919. Serial No. 283,226.

To all whom it may concern:

Be it known that I, JOSEPH MEDITZ, a citizen of Austria, residing at Brooklyn, Kings county, State of New York, have invented 5 certain new and useful Improvements in Springs, of which the following is a full, clear, and exact description.

This invention relates to improvements in springs, particularly for use in connection 10 with beds to support the apron upon which a mattress is laid. In other words, my improved spring is especially adapted for use in connection with beds that do not employ the so-called bed-springs or spring-matresses, but rather an apron which in turn 15 is held or connected to a bed frame by springs. One of the objects of my invention is to provide a spring for the purpose set forth that will not collect dirt or vermin. 20 To accomplish the foregoing result, my improved spring is formed to obviate corners or surfaces that would collect dirt.

I will now proceed to describe my invention in detail, the novel features of which 25 will be pointed out in the appended claims, reference being had to the accompanying drawing, wherein:—

Figure 1 is a diagrammatic plan view of a form of bed for which my improved spring 30 is especially adapted;

Fig. 2 is an enlarged perspective view thereof;

Fig. 3 is an enlarged fragmentary perspective view of an alternate manner of 35 forming one of the loops of the spring, and

Fig. 4 is a perspective view of a modified form of spring.

To accomplish the results set forth, I prefer to form the spring out of suitable material, such as spring wire, wound to form 40 a single coil, said wire being provided with intermeshing or interengaging looped portions to limit the extensibility of the spring.

Referring to Fig. 2, the spring is formed 45 out of a single strand 5 of suitable wire formed into a single coil 6, said coil acting to produce resilient yieldability. To limit the extensibility or contractibility, or in other words, the opening or closing of the 50 coil, I form the wire into loops 7 and 8 which are interengaged or passed one through the other, the loop 8 being a closed loop produced by securing that portion of the wire which is used to form said loop 8 to

the coiled portion 6 thereof, as at 9. The 55 securing at 9 may be accomplished by spot-welding, wiring or otherwise. To form a closed loop the portion 5^a of the strand of wire will be bent inwardly, as at 10, toward the coiled portion 6 to produce an end wall 60 or stop, the stop at the opposite end of the loop being formed by the curved end 11 of loop 8. The interengaging loop 12 is formed by bending the portion 5^b of the strand 5 to lie in parallelism with the end 5^c of said 65 strand, said end 5^c being an extension of the portion 5^a. The loop 8 will be formed to lie in a horizontal plane, while loop 12 will be formed to lie in a vertical plane. The outer end of the portions 5^b and 5^c will be 70 bent to form a hook 13. When used in connection with the form of bed hereinbefore mentioned one hook 13 will engage eyes 14 at the end of the apron 15 of the bed, and the other hook 13 will engage eyes 16 in the bed-frame 17. It will be apparent that my improved spring will yieldably support the 75 apron 15 and at the same time will be prevented from being broken by being extended too far or opened too much. Should the 80 weight upon the apron be sufficient to open the coil 6 to its utmost extent, the end 11 of loop 8 and end 18 of loop 12 would contact one with the other, thereby limiting the movement of the spring in the direction of 85 the arrows 19 and 20. Such a condition could exist should any considerable weight be dropped on the mattress of the bed. In this event, the breaking of the springs would be prevented by the stops mentioned. The 90 reaction of snapping back of the coil would be resisted or prevented by the contacting of the stops 10 and 18 of loops 8 and 12 respectively.

By forming a spring in the manner above 95 described, all corners or surfaces that would collect dirt are obviated, as it will be quite apparent from an inspection, of Fig. 2, that there will not be any surface upon which dirt can collect.

Instead of wiring or spot-welding the member 5^a to coil 6 as indicated in Fig. 2, I may pass said portion 5^c through the coil, as indicated in Fig. 3, thereby forming the closed loop 8 having the end wall 10.

Fig. 4 illustrates a modified form of my improved spring, in which the strand of wire is looped as at 21 and 22, said loops

100

105

being passed one through the other, the ends 23 and 24 of the loops 21 and 22, respectively, forming stops.

Having described my invention, what I claim is:—

1. A spring consisting of a single coil of wire formed into intermeshing loops, the loops being formed in that portion of the wire not employed to form the coil.
- 10 2. A spring consisting of a single coil of wire, that portion of the wire not employed to form the coil being bent over to form interengaging loops, one of said loops being closed, the other loop being an open loop.

3. A spring consisting of a single coil of wire, said coil at one end terminating in an open loop, the other end of the coil also terminating in a loop which engages the loop first named, the second named loop being closed, and means to connect the coiled portion of the spring to the adjacent bent over portion of the wire to form the closed loop.

Signed at New York city, N. Y., this 15 day of March, 1919.

JOSEPH MEDITZ.
